PAN LIFTER

Bertha Schultz, Lincoln, Nebr., assignor of one-third to Frank V. Schultz and one-third to Howard W. Schultz, both of Dallas, Tex.

Application August 4, 1943, Serial No. 497,375

1 Claim. (Cl. 294—27)

This invention relates to pan lifters, and its general object is to provide a device of that character which is primarily designed for attachment to pie plates, pans or the like, to facilitate handling the same and especially for removing a pan from an oven, as such can be accomplished in an easy and expeditious manner, without damaging the contents of the pan, or the user becoming burnt, and the device can be readily attached and removed with respect to the pan but casual removal or displacement is practically impossible.

A further object is to provide a pan lifter that is simple in construction, inexpensive to manufacture, and extremely efficient in use and service.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a perspective view of the device which forms the subject matter of the present invention.

Figure 2 is a side view illustrating the device attached to a pan.

Figure 3 is a fragmentary top plan view of Figure 1, with the pan in horizontal section.

Referring to the drawing in detail, the letter A indicates a pie plate or pan that includes the usual outwardly inclined side wall B formed with a marginal flange C having a downwardly directed annular rounded bead D about its upper edge, as shown in Figure 2.

The device in the form shown includes a handle provided with a relatively long shank 1 formed on and aligned with an elongated gripping member 2, the latter being round in cross section and may have a transversely disposed hole 3 therethrough, adjacent its outer end, for receiving suitable supporting means such as a nail for suspending the device therefrom, when not in use.

The outer end of the shank is slightly enlarged and formed thereon is a flat lug 4 disposed at an inclined angle to the shank. Welded or otherwise fixed to the outer face of the lug 4 is an arcuate strip like member 5 curved to follow the circumferential shape of the side wall B of the

pan, the strip member being fixed midway its ends, to the lug for disposal an equal distance upon the opposite sides thereof, as best shown in Figure 3. Formed on or otherwise secured to the strip member 5, adjacent to its outer end to project from the outer face thereof, are substantially conical knobs 6, to bear against the side wall B.

Formed on and rising at a rearward inclination midway the upper edge of the strip member is an elongated tongue 7 that is bowed rearwardly intermediate its ends, as at 8 and is tapered inwardly throughout its height as well as terminates in a rearwardly flared upper end portion having a substantially sharp edge 9 to be seated at the juncture of the bead D with the under face of the flange C, as shown in Figure 2, to cooperate with the intermediate portion of the strip member that bears against the wall B, as best shown in Figure 3 to support the pan. The bearing engagement 20 of the knobs 6 with the wall B prevents lateral movement of the pan relative to the device, with the result it will be seen that the pan is firmly held against casual removal or displacement and can be readily lifted and carried by the device, yet the latter can be attached and removed with respect to the pan in an easy and expeditious manner.

It is thought from the foregoing description that the advantages and novel features of the invention will be readily apparent.

It is to be understood that changes may be made in the construction and in the combination and arrangement of the several parts, provided that such changes fall within the scope 35 of the appended claim.

What I claim is:

A lifter and handling device for a pan having a side wall formed with a beaded flange, and said device comprising a handle, a strip secured 40 midway its ends to the handle and being curved to follow the circumferential shape of said wall and to bear against the same, a tongue formed on and rising from the strip midway its ends and rearwardly inclined therefrom, said tongue being 45 rearwardly bowed intermediate its ends and the upper end thereof being adapted to engage the bead, and knobs secured to the strip adjacent to the outer ends thereof to bear against said wall.

BERTHA SCHULTZ.
